(57) CLAIM

We claim the ornamental design for a seat, as shown and described.

DESCRIPTION

FIG. 1 is a front left perspective view of a seat having our new design;

FIG. 2 is a front view of the seat of FIG. 1; and, FIG. 3 is a side view of the seat of FIG. 1.

The dash-dot lines in the figures represent boundaries of the design that form no part of the claim. The dash-dash lines represent optional features, such as nail heads, and other portions of the seat that form no part of the claimed design.

1 Claim, 3 Drawing Sheets
